UNITED STATES PATENT OFFICE.

CHARLES E. HARRIS, OF BRAZIL, INDIANA.

TOOL.

Application filed July 19, 1924. Serial No. 727,017.

To all whom it may concern:

Be it known that I, CHARLES E. HARRIS, a citizen of the United States, residing at Brazil, in the county of Clay and State of Indiana, have invented new and useful Improvements in Tools, of which the following is a specification.

This invention relates to tools especially adapted for handling railroad ties and other heavy timber, an object being to provide a tool by means of which a tie may be readily removed from or placed in position beneath the rails of a track.

Another object of the invention is the provision of a tool designed to facilitate handling ties piled one upon the other, means being provided for separating a tie from the pile so that the said tie may be securely engaged by the tool for its convenient removal.

With the above and other objects in view, the invention further includes the following novel features and details of construction, to be hereinafter more fully described, illustrated in the accompanying drawings and pointed out in the appended claim.

In the drawings:—

Figure 1 is a plan view showing a fragmentary portion of a railroad track and illustrating the use of the invention.

Figure 2 is a top plan view of the tool per se, parts being broken away.

Figure 3 is a sectional view on the line 3—3 of Figure 2.

Referring to the drawings in detail wherein like characters of reference denote corresponding parts, the reference character R indicates the rails of a track which are supported upon ties T in the usual manner.

The tool which is designed to facilitate handling the ties for their convenient removal and replacement, comprises a body 10 which is provided with an opening 11 extending transversely through the body. Extending from one end of the body is a handle 12 at the outer end of which is a hand grip 13.

Extending laterally from opposite sides of the body 10 are substantially L-shaped gripping arms 14. The inner ends of these arms extend into and are slideable through the opening 11 and their opposed faces are provided with rack teeth 15. The teeth 15 are engaged by a gear 16 which is mounted for rotation within the opening 11, the said

gear being rigid with the inner end of a crank arm 17. The inner end of this arm 17 is mounted in bearings provided in the body 10 and forms a shaft upon which the gear 16 is secured. The outer end of this arm is disposed in juxtaposition to the grip 13 so that the operator may use one hand for holding the tool and the other hand for manipulating the crank arm 17.

The outer ends of the arms 14 are provided with inwardly disposed engaging members or teeth 18 so that when the arms 14 are moved relatively inward the teeth 18 will bite into the opposite sides of a tie T or other timber and hold the tool in clamping engagement therewith. The tie or timber may thus be conveniently handled by the use of the tool.

For the purpose of facilitating the application of the tool to ties or timbers piled one upon the other, the tool has extending from the outer end of the body 10 a separating point or wedge 19 which may be inserted between the ties or timbers and the tool manipulated to separate the tie or timber from the remainder of the pile sufficiently to permit the gripping arms to be engaged.

It will be apparent from the foregoing description and accompanying drawings that the invention provides an exceedingly simple, efficient and easily manipulated tool by means of which heavy timbers such as railroad ties and the like may be easily handled.

The invention is susceptible of various changes in its form, proportions and minor details of construction and the right is herein reserved to make such changes as properly fall within the scope of the appended claim.

Having described the invention what is claimed is:—

A tool comprising an elongated body having an opening extending transversely therethrough, a handle extending from one end of and rigid with the body, a gear mounted for rotation within the opening, oppositely disposed toothed bars engaging the gear and extending from the opening, gripping means at the outer ends of the bars and a handle rigid with and extending from the gear in the direction of the body handle.

In testimony whereof I affix my signature.

CHARLES E. HARRIS.
